B. P. JOYCE,
COUPLING,
FILED OCT. 9, 1922.

UNITED STATES PATENT OFFICE.

BRYAN P. JOYCE, OF DAVENPORT, IOWA.

COUPLING.

Application filed October 9, 1922. Serial No. 593,362.

(FILED UNDER THE ACT OF MARCH 3, 1883, 22 STAT. L., 625.)

To all whom it may concern:

Be it known that I, BRYAN P. JOYCE, a citizen of the United States, and a resident of Davenport, county of Scott, and State of Iowa, have invented an improvement in Couplings, of which the following is a specification.

The invention described herein may be used by the Government, or any of its officers or employees in prosecution of work for the Government, or by any other person in the United States, without payment to me of any royalty thereon.

This invention relates to a connection intended primarily for connecting a gun barrel with its recoil piston rod.

The main object of the invention is the provision of a connection through which the members may be readily assembled and disassembled.

A further object of the invention is the provision of a simple, cheap and efficient connection.

With these and other objects in view which will appear as the description proceeds, my invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawing, wherein:

Fig. 1 is a view in side elevation of a connection constructed in accordance with the invention;

Fig. 2 is a rear elevation of the same.

Referring to the drawing by numerals of reference:

The breech end 10 of a gun barrel is formed with a recoil lug 11 provided with a bore 12 for the reception of the end of a recoil piston rod 13, which rod has cut therein an annular groove 14.

The lug 11 is provided with a transverse slot 15 communicating with the bore 12, in which is mounted a slide 16 formed with a keyhole slot or opening 17 the enlarged portion of which slot is of sufficient diameter to permit the passage therethrough of the reduced end of the piston rod 13 and the small-

er or restricted portion of which snugly 55 embraces that portion of the rod forming the bottom of the groove 14 when the slide is pushed to its left hand position, as shown in broken and dotted lines in Fig. 2.

For the purpose of locking the slide at either 60 its right hand or left hand positions, I provide a key 18 urged toward locking position by means such as the coil spring 19 and provided with a knob 20 to permit of manual release of the key. This key 18 seats in the 65 large portion of the key hole slot when the slide is in its left hand position, as seen most clearly in Fig. 2 and, by contact with the edge of such slot, holds the slide against displacement to the right, while, with the slide 70 moved to the right, the key seats in the aperture 21 formed in the slide and so holds the slide against movement.

To permit the slide to be easily moved from one position to the other I provide 75 ears or lugs 22 and 23 on respective ends thereof which serve to limit the movement of the slide to the right or left.

The reduction of the end of the rod 13, while not essential for the purpose of this 80 invention, is a great convenience as it forms a shoulder on the rod adapted to contact the slide and so properly position the members for coupling engagement.

I claim:

1. The combination with a gun barrel formed with an apertured connecting lug having a transverse slot communicating with the aperture and a rod adapted to enter the aperture, said rod provided with 90 an annular groove, of a slide in the slot formed with a key hole opening the enlarged portion of such opening permitting the passage therethrough of the end of the rod when the slide is in unlocked position and 95 the restricted portion of the opening adapted to seat in the groove to lock the rod to the lug when the slide is moved to locked position and a spring pressed plunger mounted in the lug and operable to releasably hold the slide in locked or unlocked 100 positions.

2. The combination with a connecting lug having an aperture and a slot communicating with the aperture, of a rod adapted to 105 enter the aperture and formed with an annular groove, a slide in the slot formed with a key hole opening therein to permit pas-

usage of the rod when in one position and to seat in the groove when in another position, means for limiting the movement of the slide and means for releasably holding the slide in either position.

3. A connecting lug formed with an aperture and a slot communicating with the

aperture, a rod adapted to enter the aperture and formed with a groove, a slide in the slot and embracing the rod, movable to one position to release the rod and to another position to enter the groove and lock the rod in place.

BRYAN P. JOYCE.
